(57) **CLAIM**

The ornamental design for a handle for a cooking appliance as shown and described.

DESCRIPTION

FIG. 1 is a perspective view of a handle for a cooking appliance showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of an exemplary cooking appliance showing the handle for a cooking appliance.

The broken lines are for environmental purposes only and do not form any part of the claimed design.

1 Claim, 3 Drawing Sheets
